(57) CLAIM

The ornamental design for a dog toy as shown and described.

DESCRIPTION

FIG. 1 is a front-perspective view of a dog toy configured to support a plurality of bone-shaped dog treats within the bone-shaped recesses of the toy.

FIG. 2 is a front view of the dog toy of FIG. 1.

FIG. 3 is a top view of the dog toy of FIG. 1; and,

FIG. 4 is an end-perspective view of the dog toy FIG. 1. The broken lines illustrate a portion of the dog toy and does not form part of the claimed design.
